UNITED STATES PATENT OFFICE.

FREDERICK M. LASERSON, OF NEW YORK, N. Y.

POCKET-MARKING MACHINE.

1,353,051.

Specification of Letters Patent. Patented Sept. 14, 1920.

Application filed June 30, 1919. Serial No. 307,671.

To all whom it may concern:

Be it known that I, FREDERICK M. LASERSON, a citizen of Great Britain, and resident of New York city, in the county of New York and State of New York, have invented certain new and useful Improvements in Pocket-Marking Machines, of which the following is a specification.

This invention relates to pocket marker machines. More particularly, this invention relates to a type of hand operated machines for marking pockets, button holes and the like on garments while manufacturing the same.

The object of the invention is to provide a machine of this character adapted to be manufactured at a low cost and easily and efficiently operated. One object of the invention is to provide a machine so arranged that the operator may handle it easily and whereby a very rigid and steady apparatus is obtained.

In the accompanying drawing illustrating the invention

Figure 1 is a side elevation of a machine embodying my invention;

Fig. 2 is a rear elevation of the machine;

Fig. 3 is a bottom view of the machine;

Fig. 4 is a sectional detail view; and

Fig. 5 is a detail view of the mark locating finger.

In using the machine the operator moves it over the garments which are placed in a pile of several layers and the points to be marked by perforations through the several layers of cloth are marked on the latter with chalk or otherwise. It is therefore quite necessary that the machine be made light and also rigid so that accurate work may be obtained and the machine easily moved from place to place on the cloth. It is also essential that the operator has an unobstructed view of the marks on the cloth.

With these objects in view the machine is provided with a relatively heavy open work base 5 to which is secured a needle guide 6 in the form of a bracket extending across the base with the aperture 7 for the needle located preferably centrally of the bracket.

To one side of the base there is secured an upright hollow column 8 which forms a handle supporting portion 9 at its upper end

as shown. The top of the upright 8 is closed with a cap 10 which forms a handle or knob as shown and there is secured a spring 11 within said upright. To the lower end of the spring there is secured a block or follower 12. The column is provided with a slot 13. 14 is a motor bracket secured to said block 12 by means of a screw 14^a which passes through said bracket, through the slot 13 and into the follower. The shank 15 of the screw serves as a means for preventing rotation of the bracket 14. To the latter is secured an electric motor 16 which rotates the perforating needle 17. To the motor bracket is secured a connecting plug 18 from which a cable 19 leads to the motor. 20 is a stop collar on the column or upright 8 for the motor bracket and 21 is a handle or knob on the motor.

In operation the machine is placed over the proper marks on the cloth with the needle in register with said marks. The machine is easily lifted and placed over the mark by using the left hand or both hands.

Thereafter the operator keeps the machine steady with the left hand grasping the handle or knob 10 and with the right hand he grasps the handle 21 and presses downward thereby feeding the needle through the garments, it being understood that the machine is connected to a source of electric current by a suitable connection, not shown, which is connected to the plug 18.

In feeding the needle downward, the operator pushes against the force of the spring 11 as is obvious. When the marking is completed the operator lets go with the right hand and then the spring pulls the motor bracket and motor upward until the bracket 14 abuts the stop collar 20.

It will thus be seen that during the operation the machine is kept steady with the one hand and whereby the base is also pressed down upon the goods keeping them smooth and insuring a vertically downward working of the needle so that exact work results.

In order to assist the operator in locating the marks upon the cloth, there may be attached to the needle guide 6 a mark locating finger 25 having a hole 26 in axial alinement with the needle aperture 7. The finger 25 slides over the cloth in contact therewith and thus makes it easy for the operator to

place the machine with the needle in proper register with the mark on the cloth, as will be understood.

I claim.

- 5 A pocket marking machine comprising an open work base, provided with an aperture, a tool guide secured to said base and having an aperture in alinement with the aperture aforesaid, a slotted upright secured to said base, a block within said upright, a motor bracket surrounding said upright and adapted to slide thereon, means for connecting said motor bracket and the said block through the aforesaid slot in the upright, a
- 10

motor supported in said motor bracket, a 15 marking tool carried by said motor and adapted to operate through the apertures aforesaid, means for depressing said motor and tool, a stop secured on said upright and a spring within the latter and attached to 20 the said block for automatically lifting said motor and tool after the same has been depressed.

Signed at New York, in the county of New York and State of New York this 28th day 45 of June, A. D. 1919.

FREDERICK M. LASERSON.
